UNITED STATES PATENT OFFICE

147,374

DESIGN FOR A BED LAMP

Victor Nemeroff, Chicago, Ill.

Application May 10, 1946, Serial No. 129,552

Term of patent 14 years

(Cl. D48—19)

To all whom it may concern:

Be it known that I, Victor Nemeroff, a citizen of the United States of America, residing at 2000 Fulton Street, Chicago, Illinois, have invented a new, original, and ornamental Design for a Bed Lamp, of which the following is a specification, reference being made to the accompanying drawing, forming a part thereof.

Referring now to the drawings, Fig. 1 is a top plan view of a bed lamp embodying my new design; Fig. 2 is a front elevational view; Fig. 3 is a bottom plan view; Fig. 4 is an end elevational view; and Fig. 5 is a perspective view on a smaller scale of the same.

I claim:

The ornamental design for a bed lamp, substantially as shown.

VICTOR NEMEROFF.
